UNITED STATES PATENT OFFICE

119,448

DESIGN FOR AN AUTOMOBILE HOOD SIDE PANEL

Robert Cadwallader, Detroit, Mich.

Application July 28, 1939, Serial No. 86,303

Term of patent 7 years

To all whom it may concern:

Be it known that I, Robert Cadwallader, a citizen of the United States, residing at 17530 Fennington Drive, in the city of Detroit, county of Wayne, and State of Michigan, have invented a new, original, and ornamental Design for Automobile Hood Side Panels, of which the following is a specification, reference being had to the accompanying drawing, forming part thereof, in which:

Fig. 1 is a top plan view of an automobile hood side panel showing my new design.

Fig. 2 is a side elevation of the hood side panel shown in Fig. 1.

Fig. 3 is an enlarged sectional view taken on line 3—3 of Fig. 2.

Fig. 4 is an enlarged sectional view taken on line 4—4 of Fig. 2.

I claim:

The ornamental design for an automobile hood side panel, substantially as shown.

ROBERT CADWALLADER.
